(57) **CLAIM**

The ornamental design for an auxiliary display, as shown and described.

DESCRIPTION

FIG. 1 is a front view of an auxiliary display in an open configuration according to a first embodiment;

FIG. 2 is a rear view thereof;

FIG. 3 is a top plan view thereof;

FIG. 4 is a left side view thereof;

FIG. 5 is a bottom plan view thereof;

FIG. 6 is a top front right perspective view of the auxiliary display of FIG. 1 in an alternate configuration;

FIG. 7 is a top rear right perspective view of thereof;

FIG. 8 is a rear right perspective view thereof, including environmental features of a laptop computer and a wired connector connecting the laptop computer to the auxiliary display according to the first embodiment;

FIG. 9 is a rear left perspective view thereof, including the environmental features of FIG. 8;

FIG. 10 is a front right perspective view of the auxiliary display of FIG. 1 in an open configuration, including environmental features of a laptop computer and a wired connector connecting the laptop computer to the auxiliary display according to the first embodiment;

FIG. 11 is a rear left perspective view thereof, including the environmental features of FIG. 10;

FIG. 12 is a front view of an auxiliary display in an open configuration according to a second embodiment;

FIG. 13 is a rear view thereof;

FIG. 14 is a top plan view thereof;

FIG. 15 is a left side view thereof;

FIG. 16 is a bottom plan view thereof;

FIG. 17 is a top front right perspective view of the auxiliary display of FIG. 12 in an alternate configuration;

FIG. 18 is a top rear right perspective view of thereof;

FIG. 19 is a rear right perspective view thereof, including environmental features of a wired connector connected to the auxiliary display of the second embodiment;

FIG. 20 is a rear left perspective view thereof, including the environmental features of FIG. 19;

FIG. 21 is a front right perspective view of the auxiliary display of FIG. 12 in an open configuration, including environmental features of a wired connector connected to the auxiliary display; and,

FIG. 22 is a rear left perspective view thereof, including the environmental features of FIG. 21.
